UNITED STATES PATENT OFFICE

2,505,271

PUMP

James E. Bevins, Ramsey Estates, N. J., assignor
to Bendix Aviation Corporation, Teterboro,
N. J., a corporation of Delaware

Application April 9, 1947, Serial No. 740,309

4 Claims. (CL. 103—171)

1

The invention hereof relates to pumps and particularly to pumps of the piston type.

Among the objects of the invention are to overcome disadvantages of former pumps, and to do so by novel effective means.

Another object is to provide a pump of utmost simplicity and resistance to shock and vibration, as when mounted directly on an engine housing.

Another object is to reduce the number of parts in a pump, and facilitate manufacture and assembly.

Another object is to provide a pump including an element constituting a combined valve member and piston.

Another object is to provide a valve housing having a novel arrangement of piston cylinder bores, valve chambers, and inlet and outlet conduits, ports and ducts.

Another object is to provide novel seal means between a pump housing wall or partition and a rotatable member extending through an opening of the wall.

Another object is to provide a pump which is durable in construction, economical to manufacture and effective in its operation.

These and other objects and features of the invention are pointed out in the following description in terms of the embodiment thereof which is shown in the accompanying drawing. It is to be understood, however, that the drawing is for the purpose of illustration only and is not designed as a definition of the limits of the invention, reference being had to the appended claims for this purpose.

In the drawing:

Figure 1 is a side view, partially in elevation and partially in section, of a pump constructed in accordance with the invention;

Figure 2 is an end elevation as viewed from the right of Figure 1; and

Figure 3 is a detail section, taken substantially along the line 3—3 of Figure 1.

Referring to the drawing, the device comprises a housing unit 10 including, in this instance, an outer end portion 12 of generally cylindrical form for a motor 14, and an inner end pump housing 16 constituting the sole support for mounting the unit on an engine.

A problem, in this instance, was to provide means for pumping hot oil at moderately high speed for scavenging an engine sump under atmospheric pressure, and discharging to a reservoir, in one application, at about ten to twenty pounds per square inch, and thirty gallons per hour, at six thousand revolutions per minute.

The pump housing 16 forms a transverse plane end surface 18 having an elongated inlet channel or passage 20 closed by the pump housing material, at its ends, and open along one side in the plane or surface 18. The housing 16 also forms an outlet 22 normal to, and through, the plane

2

surface 18 adjacent to one end of the channel 20 and communicating with an internal conduit 24 along, or parallel to, the channel or passage 20. The housing 16 further forms a through bore 26 along, or parallel to, the passage 20 having an intermediate portion 28, which, in this instance, is of uniform cylindrical section, extending beyond each end of the passage 20. The bore 26 forms cylindrical portion 27 adjacent to each end, and terminates in a poppet valve chamber 30, at each end, having a valve seat 32.

A port 34 communicates between each end of the channel or passage 20 and the bore portion 28. A duct 36 communicates between each end of the conduit 24 and the corresponding chamber 30.

Simple valve disc members 37, in the chambers 30 on the seats 32, are biased toward the seats by compression springs 38 between the discs and screw plug closures 40 at the outer ends of the chambers 30.

An elongated element 42, in this instance, of simple round section solid bar character, has an axially central cut out 44, and forms, at each end, a combined valve member and piston portion 46 adapted, in this instance, to open and close the corresponding inlet port 34 at about one quarter of the piston stroke. As shown in Figure 1, the top port 34 is closed and the bottom port 34 is open.

A Scotch yoke 48, is secured to the rod 42 in the cut out 44, as by screws.

The motor 14 includes an armature shaft 50 having an end extension 52 of reduced diameter and polygonal section.

A member 54, of cylindrical form, is provided with a socket portion 56 fitting the shaft 50, an opening 58 at the bottom of the socket 56 fitting the polygonal extension 52, a radial outer flange 60, and an eccentric projecting end element 62. An anti-friction bearing 64 is mounted on the eccentric element 62 and therewith constitutes a trunnion fitting the yoke 48.

A second anti-friction bearing 66 is disposed in the pump housing 16 around the socket member 56, with one side next to the flange 60.

A lock ring 68 is disposed in a groove of the socket member 56 against the inner race of the bearing 66. A ring seal 70 is disposed in a rabbet of the pump housing around the outer race of the bearing 66.

A disc 72, at the other side of the bearing 66, is provided with a tubular portion 74 extending away from the bearing, with a sealing ring 76 of axially opening substantially channel rim section embracing the outer end of the tubular portion 74 in the channel, and having one side of the channel against the socket member 56. A member 78 has a tubular portion 80 telescoping, and 55 a radially inner flange 82 axially holding, the

sealing ring 76, and is also provided with a radially outer flange 84 telescoping the flange 72 and secured, as by screws 86, to the pump housing 16 to press the flange 72 against the ring seal 70. A gasket 88 is contoured to the surface 18 and to the inlet and outlet 20 and 22 respectively, as well as to openings 90 in the pump housing for receiving studs in mounting the device on an engine.

In operation, when the suction stroke starts in one direction, the pressure in the corresponding cylinder 27 quickly drops to a value determined by the vapor pressure and the entrained gas, the corresponding inlet port 34 is uncovered, and the cylinder fills, after which it is emptied on the discharge stroke, through the corresponding discharge valve chamber 30.

The pump housing 16 is made as one integral cast block forming all of the connecting liquid conducting passageways by simple straight line drill and machine operations, plugged where necessary, and avoiding the employment of tubes, cored holes and exterior parts.

The device dispenses entirely with inlet valve members and springs, has its outlet valve members 37 and its double piston 42 of the simplest possible form, with the latter performing the double duty of piston and valve member, provides a particularly simple and effective anti-friction eccentric and Scotch yoke structure, a simple and effective seal structure, represented by the ring 76, and other features, which severally and in combination under the device a distinct advance in its field.

Although only one embodiment of the invention has been illustrated and described, various changes in the form and relative arrangements of the parts, which will now appear to those skilled in the art, may be made without departing from the scope of the invention. Reference is, therefore, to be had to the appended claims for a definition of the limits of the invention.

What is claimed is:

1. The combination of a pump and motor housing unit comprising a pump housing including an engine mounting end portion forming a transverse plane end surface and having an elongated inlet channel closed at its ends and open along one side in said surface, the pump housing forming an outlet normal to and through said plane adjacent to one end of the channel and communicating with an internal conduit along the channel, a bore along and extending beyond each end of the channel, poppet valve chambers having valve seats at the ends of the bore, a port communicating between each end of the channel and the bore, a duct communicating between each end of the internal conduit and the corresponding chamber, valve discs in the chambers, screw plugs closing the outer ends of the chambers, compression springs between the plugs and the discs, a rod in the bore having an axially central side cut out and forming a combined valve member and piston at each end adapted to open the corresponding inlet port at substantially one quarter of the piston stroke, a Scotch yoke secured to the rod in the cut out, a motor including a shaft having an end extension of polygonal section, a member having a socket telescopically fitting the shaft and an opening at the bottom of the socket fitting the extension, the socket member having a radial outer flange and an eccentric projecting end element, an anti-friction bearing on said ele-

ment and therewith constituting a trunnion fitting the yoke, and a bearing in the pump housing around the socket member having one side next to the flange.

5 2. The combination of a pump housing including a mounting end having an inlet passage extending across said end, an outlet conduit beside the passage, a bore along and extending beyond each end of the passage, poppet valve chambers at the ends of the bore having valve seats, a port communicating between each end of said passage and said bore, a duct communicating between each end of said conduit and the corresponding chamber, valve members in said chambers, outer end closures for said chambers, springs between said end closures and valve members biasing the valve members toward the seats, a rod in said bore forming at each end a combined valve member for the corresponding inlet duct and a piston, a Scotch yoke secured to said rod, a motor including a shaft, a member rotatable with said shaft having a radially outer flange and an eccentric axially extending end trunnion, an anti-friction bearing on said trunnion fitting said yoke, a bearing around said rotatable member having one side next to said flange, and a member around said rotatable member secured to the pump housing therein at the other side of said second bearing.

20 30 3. The combination of a pump housing including a plane end surface, a closed-end inlet channel across the surface having a side open in the plane of the surface, an outlet conduit beside the channel beneath the surface, a bore beneath the surface beside and extending beyond each end of the channel, poppet valve chambers at the ends of the bore, a port adjacent to each end of the channel providing communication between the channel and the bore, a duct adjacent to each 35 40 end of said conduit providing communication between the conduit and the corresponding chamber, an elongated element in the bore forming a valve member for the corresponding inlet port and a piston at each end and having a Scotch yoke or the like intermediate said pistons, and a rotatable piston driving member carrying an eccentric end extension fitting said yoke.

45 4. The combination of a housing having a plane outer surface and forming an elongated channel closed at its ends and open along one side in said surface, a through bore beneath said surface extending along and forming a valve chamber beyond each end of said channel and a piston cylinder next to each chamber, a compartment intermediate said cylinders, an inlet port communicating between each cylinder and a side of the corresponding end of the channel, and an outlet duct for each chamber.
